UNITED STATES PATENT OFFICE

138,171

DESIGN FOR A SLIP OR SIMILAR ARTICLE

Samuel H. Geffner, New York, N. Y.

Application May 4, 1944, Serial No. 113,475

Term of patent 7 years

(Cl. D3—26)

To all whom it may concern:

Be it known that I, Samuel H. Geffner, a citizen of the United States of America, residing in New York, county of New York and State of New York, have invented a new, original, and ornamental Design for a Slip or Similar Article, of which the following is a specification, reference being had to the accompanying drawing, forming part thereof.

Fig. 1 is a front view of a slip or similar article showing my new design.

Fig. 2 is a rear view thereof.

I claim:

The ornamental design for a slip or similar article, substantially as shown.

SAMUEL H. GEFFNER.
